UNITED STATES PATENT OFFICE.

GEORGE VAN WAGENEN, OF NEW YORK, N. Y.

MACHINE FOR MANUFACTURING WROUGHT-METAL SWIVELS.

SPECIFICATION forming part of Letters Patent No. 443,807, dated December 30, 1890.

Application filed August 13, 1890. Serial No. 361,931. (No model.)

To all whom it may concern:

Be it known that I, GEORGE VAN WAGENEN, a citizen of the United States, and a resident of New York, in the county of New York, 5 and State of New York, have invented certain new and useful Improvements in Machines for Manufacturing Wrought-Metal Swivels and other Articles, of which the following is a specification.

10 The invention relates to improvements in machines for the manufacture of wrought-metal swivels and other articles; and it consists in the novel elements and combination of parts described hereinafter, and particularly 15 pointed out in the claims.

Referring to the accompanying drawings, Figure 1 is a side elevation, partly in section, 20 of a machine constructed in accordance with the invention, one side of the supporting-frame being removed and the section being on the dotted line 1 1 of Fig. 2, which is a front elevation of said machine. Fig. 3 is a 25 sectional view of said machine on the dotted line 3 3 of Fig. 1 and illustrating the blank from which the swivel is to be formed in position for manipulation; Fig. 4, a perspective view of said blank from which the swivel is to be formed; Fig. 5, a sectional view of said machine on the dotted line 3 3 of Fig. 1 and 30 illustrating the parts of the machine in position for performing the first step in the formation of said blank into the swivel; Fig. 6, a perspective view of the said blank after having the ends of its transverse bar bent downward in the manner denoted in Fig. 5; Fig. 7, 35 a sectional view on the dotted line 7 7 of Fig. 8 and illustrating the position of the parts of the machine after the ends of the transverse bar of the blanks have been rolled or 40 bent into their curved form; Fig. 8, a vertical section of the machine on the dotted line 8 8 of Fig. 7 and illustrating the position of the parts of the machine while concluding the 45 operation of rolling or bending the downwardly-extending ends of the blank into their curved form; Fig. 9, a perspective view of the swivel after having been formed by the operations of the machine illustrated in Figs. 5 and 8; Fig. 10, a side elevation of a detached portion of the machine, partly in section, 50 showing the position of the parts thereof prior to the introduction of the blank thereto,

the blank being illustrated by dotted lines; and Fig. 11 is a top view of same.

Figs. 4, 6, and 9 illustrate the steps followed 55 in the formation of the blank which is shown in Fig. 4 into the completed swivel presented in Fig. 9, and in these figures A designates the swivel-rod, and B the bar welded at its center to the lower end of said rod and 60 adapted to receive between its ends the customary wheel or roller. (Not shown.)

Referring to the figures of the drawings illustrating the machine, C denotes the driving-shaft, which will be supplied with the 65 usual clutch mechanism (not shown) for stopping it at the end of each revolution, so as to permit the withdrawal of the completed swivel and the introduction of another blank, such as shown in Fig. 4, before the parts of 70 the machine are again set in motion. The driving-shaft C is journaled in the frames D D, which are of such design as to afford the requisite strength and permit the convenient introduction of the blank to and the withdrawal of the swivel from the machine, and said shaft has mounted upon it the carriers E E, hereinafter described, one being on each side of the central frame F, which is firmly secured by screws or bolts G and has upon 80 its upper surface the transverse bearing H and recess I, the former to receive the segment J and the latter the transverse bar B of the blank to be subjected to the action of the machine. The recess I has a slightly- 85 convex surface and at its ends meets the recesses L, formed in the opposite sides of the frame F and adapted to receive the ends of the bar B after the same have been bent downward to the position shown in Fig. 5. 90 At the front edge of the recesses L, which correspond exactly with each other, are the curved formers M, which constitute the front wall of said recesses and have an outline corresponding with that it is desired the ends of 95 the bar B shall have when finally withdrawn from the machine.

Upon the sides of the frame F are formed the curved ways N, through which travel the wheels O, hereinafter referred to, and in rear of the recess I the frame F is provided with the recess P to receive the toe Q, secured to or formed with the segment J.

The segment J is shown in its two positions

by full lines and dotted lines, respectively, in Fig. 1, and, as will be observed, said segment is provided with the groove R, which partly encompasses and has a hinged movement upon the bearing H. The short arm S of the segment J constitutes a jaw to hold the bar B of the swivel-blank in the recess I, as shown by full lines in Fig. 1, and is bifurcated, so as to straddle the rod A of said blank, as clearly indicated in Figs. 3, 5, and 11. The short arm S of the segment J also carries the toe Q above referred to, which is cam-shaped, and in operation forces the bar B firmly against the front wall of the recess I during the lowering of said arm or jaw S, the purpose being to have the recess I large enough to conveniently receive the bar B and by means of the toe Q to insure the said bar being firmly held preparatory to the action of bending and forming it. The toe Q protrudes below the lower surface of the jaw or arm S, and hence it binds the bar B against the front wall of the recess I just before the force of the said jaw is brought upon it. When the jaw or arm S is in its lower position upon the bar B, the toe Q is inclosed within the recess P, which is beyond the vertical plane of the recess L, so that the toe Q will not obstruct the wheels O in the operation of curving the downwardly-extending ends of the bar B. The lower surface of the arm or jaw S is slightly concave and corresponds in the line of its concavity with the convex surface or base of the recess I, as shown in Figs. 3, 5, and 7, whereby are formed at the opposite sides of the said jaw the downwardly-depending edges shown, which, upon the jaw being lowered upon the blank, first come upon the bar B prior to the ends of the latter being turned downward to the position shown in Figs. 5 and 6. The convex base of the recess I and concave lower surface of the jaw S insure the formation of the swivel with the bar B slightly arched adjacent to the lower end of the rod A and its bends of a suitable curve to secure the requisite strength and rigidity therein.

The upper arm T of the segment J curves forward and is provided with the rounded teeth V, as shown in Fig. 1, meshing with the similarly-toothed wheel W, having the side plates or flanges X and mounted on the auxiliary shaft Y, which is journaled in the frames D D, and has secured to one of its ends the weighted lever Z, which is adapted to be swung by hand either to the front or rear, as shown by dotted and full lines, respectively, in Fig. 1, and thereby to cause a definite rotation in the auxiliary shaft Y and toothed wheel W and a consequent hinged movement in the segment J on its bearing H. When the lever Z is thrown or turned to the rear, as shown by full lines in Fig. 1, the wheel W, engaging the teeth of the segment J, moves the latter downward and forward on its bearing H to the position shown by full lines in Fig. 1 and closes the arm or jaw S upon the bar B, and

when the lever Z is turned to the front, as indicated by dotted lines in Fig. 1, it will reverse the movement of the shaft Y and wheel W and cause the latter to turn the segment J upward and rearward on its bearing H, thereby elevating the jaw S from the swivel and leaving the latter exposed and free to be conveniently removed. The wheel W, in addition to effecting the movement of the segment J on its bearing H, is in line with the said bearing, and hence prevents any upward movement of the jaw S during the operation of bending and forming the bar B. Any tendency of the jaw S to rise under the action of the bar B is firmly and effectually resisted by the wheel W, which only permits the elevation and depression of the segment J when the lever Z is turned by hand either to the front or rear, as indicated in Fig. 1. The plates or flanges X on the wheel W insure the meshing of the teeth of the segment J with those of the wheel at all times and prevent any lateral play in the upper arm of said segment.

The carriers E E have hubs a a, by which they are secured to the driving-shaft C, one of said carriers being on each side of the frame F, and upon said carriers are secured on suitable axes the rollers b b and wheels O O, as shown in Figs. 1 and 2. The rollers b b are in the form of truncated cones whose axles d d are mounted in the bearings e, which are held in place upon the front surfaces of the carriers E E by the bolts or screws f, the latter passing through elongated slots i in said bearings, so as to render the latter, with the rollers b b, adjustable toward or from the vertical faces of the frame F in accordance with the thickness of the bar B. Upon the outer face of the carriers E E are bolted the plates j, having set-screws m at their ends, the purpose of the set-screws being to aid the screws f in rigidly retaining the bearings e in place upon the carriers during the operation of bending the bar B and prevent any lateral or outward play in the rollers b b while in use. The object of the rollers b b is to bend the ends of the bar B downward from the position shown in Figs. 3 and 4 to that illustrated in Figs. 5 and 6, and their method of accomplishing this will be described hereinafter.

The wheels O O are mounted on axles on the inner facing sides of the carriers E E and are provided with the annular grooves n, formed by the flanges t u, the grooves being of sufficient width to snugly receive the thickness of the ends of the bar B after the rollers b b have turned said ends downward, and the flanges u being of a depth equal or about equal to the width of the bar B, so that said bar may, while being given the form shown in Figs. 8 and 9, have its ends within the grooves n and be prevented from twisting or becoming irregular under the action of the wheels O O. It will be observed upon reference to Fig. 7 that the flanges u of the wheels O O travel

in and are inclosed above and below by the ways N, formed in the opposite sides of the frame F, thus leaving the annular grooves n in position to admit the ends of the bar B and bringing the main body of the wheels O O between the flanges t u in line with said ends of the bar B, the object being during the rotation of the carriers E E, with the driving-shaft C, to have that portion of the wheels O O between the flanges t u come into contact with and curve the ends of the bar B around the formers M, as indicated in Fig. 8, while the grooves n snugly receive said ends and firmly hold them against twisting or other lateral play.

Preparatory to the use of the machine the bar B is welded to the lower end of the rod A, after which the blank in a heated condition is placed in the recess I, with the rod A extending upwardly centrally therefrom, the segment J having previously been thrown upward to the position shown by dotted lines in Fig. 1 by the movement of the lever Z and wheel W. After the blank is in position the lever Z and wheel W are reversed in their movements and the segment J thus lowered, bringing the jaw S upon the blank, as shown in Figs. 1 and 3, whereupon the driving-shaft C makes one complete revolution and thereby causes the carriers E E to rotate in the line of a circle, following the direction of the arrow in Fig. 1, the effect being that the rollers b b are first brought against the ends of the bar B and bend them downward on opposite sides of the frame F, as shown in Fig. 5, and then that the wheels O O follow along and bend or curve said downwardly-bent ends of the bar B against the formers M, as shown in Fig. 8, after which the segment J will be elevated by the lever Z and the now-finished swivel be removed and another blank inserted in the recess I preparatory to its formation into a swivel by the next succeeding revolution of the driving-shaft C. At each revolution of the driving-shaft C a swivel is formed by the rollers b b and wheels O O, and after being formed the swivels may receive the customary wheels or rollers between the ends of the bar B preparatory to their application to the front of a sugar-wagon, such as that shown in Letters Patent of the United States No. 428,790, issued to the George Van Wagener Company May 27, 1890, or to any other article requiring them.

Where the two carriers E, with their rollers and wheels, are made use of both ends of the blank may at one operation be bent and curved; but it is obvious that one carrier may be omitted and the swivel formed by first shaping one of its ends and then reversing it and shaping the other end, thus requiring two operations.

The single machine with but one carrier I do not consider as advantageous as the machine with both carriers; but it is to be understood that such machine is within the scope of my invention as claimed.

The lever Z is weighted to facilitate the operation of the segment J, and said weight may be adjusted as occasion may require. 70

What I claim as my invention, and desire to secure by Letters Patent, is—

1. The frame having the recess to receive the blank and the jaw for holding said blank in position, combined with the carriers connected with the driving-shaft and carrying the rollers and wheels for bending and curving the ends of said blank, substantially as set forth. 75

2. The frame to receive the blank and the jaw for holding the same in position, said frame having the curved formers, combined with the carriers connected with the driving-shaft and being one on each side of said frame, the rollers secured to the front of said carriers 85 for bending the ends of the blank downward, and the wheels secured to the inner faces of said carriers for curving or bending the ends of the blank around said formers, substantially as set forth. 90

3. The frame to receive the blank and the jaw for holding the same in position, said frame having the curved former, combined with the carrier connected with the driving-shaft and carrying the roller and wheel for 95 first bending the end of the blank downward and then curving it on said former, substantially as set forth.

4. The frame to receive the blank and the hinged segment consisting of the connected 100 jaw and toothed arm, the jaw being to hold the blank in place, combined with the toothed wheel and lever for operating the said segment, the carriers connected with the driving-shaft, the rollers secured to the carriers for 105 bending the ends of the said blank downward, and the wheels also secured to said carriers for curving said ends, substantially as set forth.

5. The frame to receive the blank and rollers for bending the same, combined with the rocking segment consisting of the connected 110 jaw and toothed arm, the toothed wheel engaging said segment, and the lever for turning said wheel and thus to actuate the segment, substantially as set forth. 115

6. The frame to receive the blank and rollers for bending the same, combined with the rocking segment consisting of the connected 120 jaw and toothed arm, the toothed wheel engaging said segment and having flange-plates on opposite sides, and the weighted lever for turning said wheel and thus to actuate the segment, substantially as set forth.

7. The frame having the recess to receive 125 the blank and rollers for bending the same, combined with the rocking segment consisting of the connected jaw and toothed arm, the toe connected with said jaw for binding the blank in said recess, the toothed wheel engaging said segment, and the lever for operating said wheel and thus to move the segment, substantially as set forth. 130

8. The frame having the recess to receive

the transverse bar of the blank while the swivel-rod thereof extends upward and rollers for bending the same, combined with the rocking segment consisting of the connected toothed arm and bifurcated jaw, the toothed wheel engaging said toothed arm, and the lever for turning said wheel and thus to actuate the segment, substantially as set forth.

9. The frame having the bearing H and the recess to receive the blank and the rollers for bending the same, combined with the segment having the groove to rest upon said bearing and consisting of the connected jaw and toothed arm, the wheel engaging said arm, and the lever for turning said wheel, substantially as set forth.

10. The frame to receive the blank and the jaw for holding the same, combined with the carriers connected with the driving-shaft and carrying the rollers for bending the ends of the blank and the grooved wheels for receiving and curving said ends on formers, substantially as set forth.

11. The frame to receive the blank and the jaw for holding the same, combined with the carriers connected with the driving-shaft and carrying the truncated cone-shaped rollers for bending the ends of the blank and the grooved wheels for curving said ends, the grooves in said wheels being of sufficient width and depth to contain the ends of the blank, substantially as set forth.

12. The frame to receive the blank and the jaw for holding the same, combined with the carriers connected with the driving-shaft and carrying the rollers and grooved wheels for

bending and curving the ends of said blank, the said rollers being mounted in adjustable bearings, substantially as set forth.

13. The frame to receive the blank and having the ways N and formers M and the jaw for holding the blank in position, combined with the carriers carrying the rollers b b on the front face and the flanged wheels on their facing sides, the inner flange of the 45 wheels traveling in said ways, substantially as set forth.

14. The frame having the recess to receive the blank and the ways on its opposite sides, combined with the rocking segment consisting of the connected toothed arm and jaw, the toothed wheel engaging said segment, the lever for turning said wheel, the carriers connected with the driving-shaft, the rollers on said carriers for bending the ends of the blank, 55 and the flanged wheels on the facing sides of said carriers for curving said ends, substantially as set forth.

15. The frame to receive the blank, combined with the jaw to hold the same, the carrier connected with the driving-shaft, and the roller and grooved wheel secured to said carrier for bending and shaping the blank, substantially as set forth.

Signed at New York, in the county of New 65 York and State of New York, this 12th day of August, A. D. 1890.

GEORGE VAN WAGENEN.
